DEVICE FOR ROLLING-OVER THE EDGES OF
FLAT-FLANGED DISHED CAN BOTTOMS
OR LIDS

Werner Moser, Lenzburg, Switzerland

Application February 28, 1950, Serial No. 146,906
In Switzerland December 29, 1949

4 Claims. (Cl. 153—59)

1

The invention relates to the rolling-over of the edges of dished can bottoms or lids.

It is well known in the art to produce dished can bottoms or lids with turned-up flanges, as required for attaching such bottoms or lids to the can mantles, by stamping and pressing. However, the stamping and pressing tools required therefor are complicated and expensive and need repeated and likewise expensive maintenance as compared with the tools required for the production of can bottoms or lids having completely flat flanges which will be referred to as "flat-flanged dished can bottoms or lids."

On the other hand such flat-flanged dished can bottoms or lids can not be attached as such to the can mantles, but want rolling-over of their edges preparatory to attaching. Devices for such rolling-over have been suggested wherein the flat-flanged dished can bottoms or lids are fed one after the other between the bottom ends of at least three rollers which are continuously driven in the same direction and taper conically downwards and which have a screw-thread like rolling-over groove, these grooves grasping the edge of the flat-flanged dished can bottom or lid and lifting it parallel to itself and, in so doing, effecting the rolling over of its edge, owing to the conicity of the rollers and the consequent reduction of the distance between the rolling-over grooves.

The main objects of the present invention are: to provide an improved rolling-over device for rolling-over the edges of flat-flanged dished can bottoms or lids; to provide an improved roller for such a rolling-over device; and to provide an improved method of rolling-over the edges of flat-flanged dished can bottoms or lids which reliably produces rolled-over edges of uniformly high quality suitable for attachment to can mantles.

Further objects will appear from the description of a typical embodiment of a rolling-over device according to the invention.

According to a main feature of the invention the improved rolling-over device comprises in combination: an inclined support plate, three identical rollers journaled relatively to and projecting from the said support plate parallel to one another in a triangular disposition, driving means arranged for rotating the said rollers in the same sense of rotation and at the same constant speed, each of the said rollers comprising a smooth cylindrical bottom portion, a helically grooved main portion of an outer radius larger than the radius of said cylindrical bottom

2

portion and a wedge shaped catcher having its bottom face flush with the bottom face of the said roller and its upper face leading up to the lower flank of a helical rolling-over groove in the said main portion of the roller the said helical groove starting with a part extending over a fraction of a turn having a root radius equal to the radius of the said bottom portion of the roller, and leading through a transition zone of steeply increasing root radius to the main part of said helical groove which gradually increases in root radius up to the last turns of said helical groove which are of constant root radius, and a chute for feeding flat-flanged dished can bottoms or lids one after the other to the bottom portions of the said rollers, the said rollers being angularly so disposed about their respective axes of rotation that their catchers simultaneously engage the flange of a can bottom or lid.

20 A method of rolling-over the edge of a flat-flanged dished can bottom or lid by rolling contact with its circumference while moving the said can bottom or lid parallel to, and at the same time rotating it about, itself comprises according to the invention the phases of simultaneously engaging the said edge at three points, applying sudden radial inward pressure causing indentations in the said edge at its three points of rolling contact, rolling-over the said edge 25 from the three indentations simultaneously by gradually increasing the radial inward pressure, and smoothing the rolled-over edge by continuing rolling contact without further radial inward pressure.

30 With these general statements of the objects and purposes of my invention I will now proceed to describe an embodiment thereof and the manner in which my invention is carried out, and it will be understood that while I have described 35 what may be considered as a preferable embodiment of my invention, I do not limit myself to the precise conditions or proportions herein set forth, as they may be varied by those skilled in the art in accordance with the particular purposes for which they are intended and the conditions under which they are utilised.

In the accompanying drawings:

Fig. 1 is a longitudinal section through an earlier type of rolling-over device;

50 Fig. 2 is a plan view thereof;

Fig. 3 is a cross section through the rolling-over groove of an improved roller according to the present invention, on a greatly enlarged scale.

55 Fig. 4 is a diametrical section through a flat-

flanged dished can bottom or lid, prior to rolling-over.

Fig. 5 is a diametrical section through a rolled-over dished can bottom or lid.

Fig. 6 is a perspective over-all view of an improved rolling-over device according to the invention.

Fig. 7 is an elevation of an improved roller according to the invention, and

Fig. 8 is a plan view thereof.

Referring first to Figs. 1 and 2, a plate 101 which is fixedly arranged on a base 102, has a T-shaped opening 103 in which are displaceably mounted three roller-carriers each of which consists of a bottom part 104 and a top part 105. In each bottom part 104 there is provided a bearing 106 and in each top part 105 there is provided a bearing 107 for a shaft 108. Between the bearings 106 and 107, there is exchangeably arranged, on each of the three shafts 108, a conical roller 109 which tapers downwardly towards the plate 101 and which has a screw-thread like rolling-over groove 110. For clamping the roller-carriers 104, 105 in the arms of the T-shaped opening 103, there are employed screws 111, which pass through the bottom part 104 and the top part 105, and clamping members 114. The shafts 106, together with their rollers 109, are continuously driven in the same direction (in any desired manner) by means of toothed wheels, 117, 118, 119, belts 116 and chains 120 from a driving shaft 115 or the shaft of a built-in electromotor not shown. An inclined guiding groove 112, which is provided with guide rails 113 for the edge of the flat-flanged can bottom or lid, serves for catching the can bottoms and lids ejected from the stamping press and for introducing them between the rollers 109 of the device which is set up in a suitable position directly near the stamping press.

Referring now to the improved device shown in Fig. 6, a support plate 2 is attached in a sloping position on a casing. This support plate 2 has a T-shaped opening, the three arms of which each form the guide for one of three slides 4 which are shiftable by means of a threaded spindle 3 journalled in the casing 1. On each of these three slides 4 a roller support bracket 5 is arranged. A shaft 6 is journalled on the one hand in the slide 4 and on the other hand in the said roller support bracket 5 on which shaft a roller 7 is keyed which will be described later in detail. Each roller support bracket 5 has a clamping screw 8 by means of which the associated slide 4 can be clamped in its guide. The shafts 6 are driven in the same sense of rotation and at the same speed by an electric motor 9 via transmission means arranged in the casing 1 at the lower side of the support plate 2 and of the slides 4, such as the gears 117, 118, 119, belt 116 and chains 120 described with reference to Figs. 1 and 2. A sloping chute 13 serves for catching the lids or bottoms dropping out of a stamping press (not shown) and for introducing the same between the rollers 7. One side wall of the chute 13 is adjustable by means of adjustment screws 15 in such a manner that the width of the chute 13 can be adapted to the diameter of the lids or bottoms. Above the chute 13 a guide baffle 16 is arranged which prevents the lids or bottoms from jumping out of or from shifting the ones on top of the others within said chute. On each roller support bracket 5 a guide rod 17 is arranged between which rods a pile of finished rolled-over

lids or bottoms is formed in the course of the operation of the rolling-over device.

The three rollers 7 (Figs. 3, 7 and 8) are constructed accurately identical, and have each a helical rolling-over groove 7a machined in them, the root of which has a step 7b (Fig. 3). The lower, deeper, part 7c of the rolling-over groove 7a which has a part-toroid profile is designed for rolling-over the edges of the lids or bottoms.

10 The depth of the rolling-over groove 7a diminishes from bottom to top except for the three uppermost turns which have constant depth. The rollers 7 have, however, a constant outer diameter.

15 At their lower ends the rollers 7 have a smooth bottom portion 7d the diameter of which is slightly smaller than the diameter of the root of the rolling-over groove 7a at its lowest deepest turn. On the lower end of the helical rolling-over groove 7a a wedge-shaped catcher 7e (Figs. 7 and 8) is arranged, the upper face of which leads over to the said helical groove, and the lower face of which lies in the plane of the lower end face of the roller 7. Adjacent to the catcher 7e the inner diameter of the rolling-over groove 7a is equal to the diameter of the smooth bottom portion 7d on a short stretch, i. e. over not more than a quarter turn, from where it increases in a steep transition zone 7f and hence 20 gradually increases further. The smooth bottom part 7d of the rollers 7 engages into a counterbored recess 4a in the associated slide 4 of .008"- 0.012" depth.

25 The can lids or bottoms, dropping out of the stamping press, slide down the chute 13, one after the other and the foremost of them gets between the rollers 7 which have been adjusted so that their smooth bottom portions 7d touch on three points the edge of the can lid or bottom dropping in. The rollers 7 are angularly 30 adjusted on their shafts 6 in such a manner that their catchers 7e get simultaneously into touch with the edge of a can lid or bottom situated between them. Since the edges of the wedge shaped catchers 7e reach into the counterbored recesses 4a of the slides 4, the can lid or bottom is safely caught and lifted. When the can lid or bottom gets between the rollers 7 during their rotation too late i. e. when the edges of the catchers 7e have already passed their innermost positions, it slides laterally off these catchers 7e and remains where it was, whereby it prevents the next subsequent can lid or bottom from entering between the rollers 7. At 35 the next revolution of the rollers 7 this can lid or bottom that was left behind previously, is then caught and raised by the catchers 7e.

40 In Fig. 7 part of a flat flanged can lid 18 (Fig. 4) is represented in chain-dotted lines, resting on the slide 4 in the condition in which it comes from the stamping press. This lid 18 is now caught by the catchers 7e of the uniformly 45 revolving rollers 7 and is raised thereby. The depth of the rolling-over groove 7a at the start is slightly larger than the width of the flange of the lid 18 whereby the dished middle portion of this lid 18 is caught and guided in the rolling-over groove. After a rotation of the rollers 7 of not more than a quarter turn the zone of transition 7f comes into touch with the lid 18, and by the sudden reduction of depth of the rolling-over groove 7a at this point the edge of the lid 18 is dented simultaneously on three 50 points corresponding to the three rollers 7, whereby it is centered.

In Fig. 7 part of a second lid 18', preceding the lid 18 in operation, is shown in chain-dotted lines, the dent at its edge being indicated. After this denting, the edge is gradually rolled-over from these three dents onward, while the lid 18' is held between, and lifted and rotated by, the said rollers until it reaches the three uppermost turns 1g of the helix which are of constant depth and have an equalizing effect on the rolled-over edge of the lid 18.

The finished rolled-over lids or bottoms 18" (Fig. 5) are piled up between the three guide rods 17 (Fig. 6) and can be taken off from the top of the staple thus formed.

What I claim as my invention and desire to secure by Letters Patent, is:

1. A device for rolling-over the edges of flat-flanged dished can bottoms or lids comprising an inclined support plate, three identical rollers journalled relatively to and projecting from the said support plate parallel to one another in a triangular disposition, driving means arranged for rotating the said rollers in the same sense of rotation and at the same constant speed, each of the said rollers comprising a smooth cylindrical bottom portion, a helically grooved main portion of an outer radius larger than the radius of said cylindrical bottom portion and a wedge shaped catcher having its bottom face flush with the bottom face of the said roller and its upper face leading up to the lower flank of a helical rolling-over groove in the said main portion of the roller the said helical groove starting with a part extending over a fraction of a turn having a root radius equal to the radius of the said bottom portion of the roller, and leading through a transition zone of steeply increasing root radius to the main part of said helical groove which gradually increases in root radius up to the last turns of said helical groove which are of constant root radius, and a chute for feeding flat-flanged dished can bottoms or lids one after the other to the bottom portions of the said rollers the said rollers being angularly so disposed about their respective axes of rotation that their catchers simultaneously engage the flange of a can bottom or lid.

2. A device for rolling-over the edges of flat-flanged dished can bottoms or lids as claimed in claim 1 comprising a guide baffle arranged on top of said chute at a distance corresponding to the depth of dishing of the said can bottoms or lids for preventing their jumping out of, or their shifting the ones on top of the others within, the said chute.

3. A device for rolling-over the edges of flat-flanged dished can bottoms or lids as claimed in claim 1 comprising an adjustable side wall of the said chute and adjusting means for adjusting the said side wall to a width of the chute corresponding to the outer diameter of the said can bottoms or lids.

4. A device for rolling-over the edges of flat-flanged dished can bottoms or lids comprising an inclined support plate, three roller carriers adjustably fixed to the said support plate and counter-bored on their upper bottom faces, three identical rollers each journalled in one of the said roller carriers with their axes parallel to one another and perpendicular to the said support plate in a triangular disposition, driving means arranged for rotating the said rollers in the same sense of rotation and at the same constant speed, each of the said rollers comprising a smooth cylindrical bottom portion fitting into and projecting from the said counterbored faces of the roller carriers, a helically grooved main portion of an outer radius larger than the radius of said cylindrical bottom portion and a wedge shaped catcher having its bottom face flush with the bottom face of the said roller and its upper face leading up to the lower flank of a helical rolling-over groove in the said main portion of the roller the said helical groove starting with a part extending over a fraction of a turn having a root radius equal to the radius of the said bottom portion of the roller, and leading through a transition zone of steeply increasing root radius to the main part of said helical groove which gradually increases in root radius up to the last turns of said helical groove which are of constant root radius, and a chute for feeding flat-flanged dished can bottoms or lids one after the other to the bottom portions of the said rollers the said rollers being angularly so disposed about their respective axes of rotation that their catchers simultaneously engage the flange of a can bottom or lid.

WERNER MOSER.
